HANDLE CONNECTION

Louis Cabana, Buffalo, N. Y., assignor to Liquid
Veneer Corporation, Buffalo, N. Y., a corpo-
ration of New York

Application October 30, 1931. Serial No. 572,082

2 Claims. (Cl. 306—23)

My invention relates to improvements in connectors, and it has more particular reference to socket connectors wherein a socket is included which is adapted to have a handle fastened thereinto.

5 Mops, brush brooms, window brushes, and other similar devices or implements invariably have comparatively long handles removably connected thereto, and these are generally inserted into 10 sockets applied to or forming part of the mop head, brush head, or the like.

The form of handle most commonly used is one having a tapered end adapted to be thrust into an opening or socket and be retained therein by frictional contact; sometimes a screw, nail, 15 or other similar retaining medium is passed or driven through a portion of the mop or other head to engage or enter the inserted end of the handle.

20 Another common form is one in which the socket is screw-threaded and the handle provided with screw threads adapted to be engaged by the screw threads in the socket.

Such means of fastening handles to mop heads, 25 brush heads and the like, are impracticable, due to the shrinkage of the wooden handles; and even with screws, nails or other retaining devices passed through the head to engage or enter the handle, the heads become wobbly on the handles. Where no such fastening devices are employed the head slips from the handle, particularly during manipulation of the device or 30 implement.

It is the object of my invention to provide a 35 simple and inexpensive connection between a handle and an implement head, which will eliminate the disadvantages above-mentioned.

Another object of my invention is to provide a socket which may form part of an implement 40 head or be secured thereto, and in which the wall of the socket is provided with an inwardly-extending protuberance, preferably formed by indenting the wall of the socket from the outer side so as to form a nub or nubs on the inner 45 face thereof, and to associate therewith a ferrule secured to the handle and having nub-receiving grooves formed in the ferrule after the latter is applied to the handle so that the fibers of the wooden handle will be compressed within the 50 ferrule under indenture of the metal of the ferrule when forming the nub-receiving groove or grooves therein.

Another object of my invention is the application of an ungrooved ferrule to a handle and 55 the formation therein of nub-receiving or retain-

er grooves after the ferrule is applied to the handle; the grooves being preferably of the type referred to as of bayonet formation, wherein at least a portion of the groove is disposed at an angle to a plane extending lengthwise of the 60 handle so as to form shoulders in the wooden handle trending in the direction of its circumference, to thereby prevent removal of the ferrule from the handle.

With these and other objects in view to appear 65 hereinafter, my invention consists in the new method of securing a ferrule to a handle; in the novel features of construction, and in the arrangement and combination of parts to be hereinafter described and more particularly pointed 70 out in the subjoined claims.

In the drawing:

Fig. 1 is a perspective view of a mop head having a socket applied thereto or forming part thereof, and of a handle having a ferrule constructed in accordance with my invention positioned to illustrate the manner of inserting the 75 handle into the socket of the mop head.

Fig. 2 is an enlarged transverse section taken on line 2—2, Fig. 1.

Fig. 3 is an enlarged transverse section taken on line 3—3, Fig. 1.

Fig. 4 is a sectional elevation, the section being taken through the part indicated by line 4—4, Fig. 1.

Fig. 5 is a similar view taken on line 5—5, Fig. 1.

Fig. 6 is a perspective view of the ferrule in the form in which it is applied to the wooden 90 handle.

In its broadest aspect, my invention includes a socket, designated by the numeral 7, which may be constructed in the manner illustrated so that it may be detachably applied to an implement head 8. In the drawing I have shown the 95 implement head formed of wire and adapted to have the socket clamped thereto, the wire being intended to receive a dusting or polishing swab. This arrangement, however, is shown for purposes of illustration only, as various types 100 of mop heads now in common use have sockets applied thereto, and various other types of heads, such as heads of brush brooms, window brushes and the like may be substituted from the head shown. In every case, however, a socket is to be 105 provided to receive the handle, and in the socket are to be one or more hubs for the purpose hereinafter set out.

The particular socket shown in the drawing 110 is constructed of sheet metal, and the metal is

indented inwardly, as at 9, to form internal nubs 10. One or more of these nubs may be employed. I have found the best results to be secured by positioning these nubs at diametrically opposite points of the socket.

11 designates the usual wooden handle, and 12 a metallic ferrule applied to one end thereof. While the ferrule may be applied to the handle without tapering the handle at the region of application, I preferably taper the handle and correspondingly taper the ferrule, and it may be here stated that the general practice is, regardless of the formation of the socket otherwise, that such socket be slightly tapered inwardly.

15 The ferrule 12 is applied to the handle when in the form shown in Fig. 6; that is to say, it is of true circular formation throughout its length. It may or may not be closed at its outer end, but to prevent the forcing of the wood outwardly beyond the outer end of the ferrule, I preferably construct the ferrule with an outer end wall 13. The ferrule in the form shown in Fig. 6, is thrust over the end of the handle, preferably tapered for the purpose, and after being applied thereto the ferrule-end of the handle is thrust between dies which are closed thereupon to create exterior retainer grooves 14 therein, the pressure exerted to form these grooves creating internal ribs in the ferrule and causing the fibers of the wood within the ferrule to be compressed, thereby assuring that even after the shrinkage of the wood, such shrinkage will have taken place only in directions at angles to the plane in which the grooves are formed in the ferrule, such grooves being preferably formed at diametrically opposite regions of the ferrule.

Moreover, it is intended that these grooves be of the common bayonet formation; that is to say, they are provided with longitudinal portions 15 and right-angled portions 16 at the inner ends of the longitudinal portions, said right-angled portions preferably terminating in recurved or re-entrant extremities 17.

It is to be particularly noted that the forming of the right-angled portions 16 of the grooves at the inner ends of the longitudinal portions 15 thereof result in the formation of circumferentially-trending shoulders 18 in the wood at diametrically opposite regions of the handle, the lower of these shoulders preventing withdrawal of the ferrule from the handle.

When connecting the handle to an implement having a socket, the ferrule end thereof is thrust into the socket 7, with the result that the nubs 9 enter the longitudinal portions 15 of the bayonet grooves 14, and as these nubs reach the inner ends of said longitudinal portions, the socket is turned upon the handle, or the handle within the socket, to cause the nubs 8 to pass through the

transverse or circumferentially-trending short groove portions 16 and enter the recurved or re-entrant portions 17 at the extremities of the grooves, the nubs 8 resting within said re-curved or re-entrant portions and preventing rotation of the handle within the socket or the socket on the handle.

The advantages of my improved ferrule will be apparent from the foregoing description, but it may be stated that heretofore, when metallic ferrules were employed, it has been necessary, in order to manufacture at a price demanded by the trade to use pins, nails, or the like which were passed through the ferrule and driven into the handle to prevent accidental or unintentional removal of the ferrule from the handle. In all cases, however, the wood of the handle becomes shrunken after a time and the ferrule is only wobbly retained on the handle. Eventually the nail or other retainer device employed to secure the ferrule to the handle becomes loosened, by wearing into the fibres of the woods, and this practically renders the handle useless or at least uncontrollable.

It may be further stated that handles of this type generally in use are exceedingly cheap and are fashioned from unseasoned material; that they often become wet and swell, and when dry shrink to subnormal diameter.

With my construction, the compressing of the wood fibers within the ferrule results in reducing the handle along a diametral region or dimension or to a size beyond that possible for the wood fibers to shrink, and assurance is had, regardless of the length of time the handle is used, that the ferrule will be securely retained thereon.

Having thus described my invention, what I claim is:

1. An implement connector, comprising a socket having a nub stamped therefrom and projecting thereinto, and a wooden handle having a metallic ferrule thereon inserted into said socket and provided with an angular exterior retainer groove adapted to receive said nub, said groove creating an angular interior rib in said ferrule forced into the fibers of the wooden handle both in the direction of the trend of said fibers and crosswise thereof.

2. In a connector for implements, a sheet metal ferrule applied to one end of a wooden handle and having an exterior retainer groove trending in different directions formed therein to create an interior rib in said ferrule, said rib being pressed into said wooden handle to form shoulders in the latter trending in directions corresponding to that of said retainer groove and thus prevent endwise and rotative movement of the ferrule from the handle.

LOUIS CABANA.
